DESIGN FOR A LOUVERED FLUORESCENT LIGHTING FIXTURE

David J. Biller, St. Louis, Mo., assignor to Day-Brite Lighting, Inc., St. Louis, Mo., a corporation of Missouri

Application February 11, 1942, Serial No. 105,768

Term of patent 14 years

To all whom it may concern:

Be it known that I, David J. Biller, a citizen of the United States and a resident of the city of St. Louis and State of Missouri, have invented a new, original, and ornamental Design for a Louvered Fluorescent Lighting Fixture, of which the following is a specification, reference being had to the accompanying drawing, forming part thereof.

Fig. 1 is a perspective view of a louvered fluorescent lighting fixture, showing my new design.

Fig. 2 is an end view looking at the opposite

end from that shown in Fig. 1, a portion of the end cap being broken away to show the louver construction more clearly; and

Fig. 3 is a bottom plan view.

The characteristic features of my design reside in those portions shown in solid lines in the drawing.

I claim:

The ornamental design for a louvered fluorescent lighting fixture, as shown and described.

DAVID J. BILLER.
